ATTORNEY

UNITED STATES PATENT OFFICE.

WILLIAM S. PERRY, OF NEW HAVEN, CONNECTICUT, ASSIGNOR TO THE WOPECO MACHINE COMPANY, OF NEW HAVEN, CONNECTICUT, A CORPORATION OF CONNECTICUT.

CAN OPENER.

Application filed December 9, 1921. Serial No. 521,173.

To all whom it may concern:

Be it known that I, WILLIAM S. PERRY, a citizen of the United States, residing at New Haven, in the county of New Haven and State of Connecticut, have invented certain new and useful Improvements in Can Openers, of which the following is a specification, reference being had therein to the accompanying drawings.

10 This invention has reference to a new and improved can opener the object of which, among other things, is to provide a device that is simple, both in its structure and operation, can be produced at the minimum 15 cost, and will open a can with the minimum expenditure of time and labor.

To these and other ends my invention consists in the can opener having certain details of construction and combinations of parts 20 as will be hereinafter described and more particularly pointed out in the claims.

Referring to the drawings in which like characters of reference designate like parts in the several figures;

25 Figure 1 is a view of the can opener as applied in operative position to a can, the cut therein being partially complete;

Figure 2 is an elevation of my improved can opener when closed;

30 Figure 3 is another elevation thereof looking toward the right of Figure 2;

Figure 4 is a perspective view of the knife carrier; and

35 Figure 5 is a view of the cutter.

In the practice of my invention I provide a base member 10 having a handle portion 11 at one end and a head portion 12 at the other end. This latter is preferably provided with laterally projecting arms 13 having, if desired, lugs 32 thereon, a tooth 14 upon the end thereof and a second tooth 15 upon the underside thereof.

40 Through the base member 10 is an opening 16 at the inner end of an opening 17 which may be provided, if desired, to reduce the weight of the base member 10.

45 The top face 18 of the tooth 14 is in substantially the same line as the underside of the base member 10 and the tooth 15 inclines 50 forwardly toward the tooth 14, as is clearly shown in Figure 3. It is desirable that the tooth 15 be so projected relatively to the tooth 14, but is not essential to the operation of the device as a tooth at a right angle to

the base member or any other angle could 55 be operated equally as successfully.

Connected with the head portion 12 is a post 19 upon which is mounted a swivel member 20 that is held against axial movement thereon by the screw 21.

60 Hinged to the swivel member 20 by the pin 22 is an arm 23 having on the outer end thereof a handle 24. Slidably mounted upon the arm 23 is a carriage 25. This is preferably formed substantially U-shape as shown 65 in Figure 4 with the free ends secured together by the studs 26 or similar means and adjacent thereto is a spring 27 which rests upon one face of the arm 23 with sufficient pressure to prevent accidental movement of 70 the carriage 25 thereon. Within this carriage 25 is mounted the cutter 28 through the shank of which is an opening 29 of substantially the same shape in cross-section as that of the arm 23, which projects there- 75 through and holds the cutter against movement in relation thereto, except when shifted along the arm with the carriage 25.

Obviously the shape of the carriage 25 and the method of associating the cutter 80 with the arm may be modified within the spirit of my invention and still perform the function required thereof, and the spring 27 can also be omitted without impairing the effectiveness of my device.

85 In Figures 2 and 3 the can opener is shown in its non-use position, at which time the arm 23 lies substantially parallel with the base member 10 and the sharpened end of the cutter 28 is projecting into the open- 90 ing 16.

With the parts in these relative positions the can opener occupies the minimum amount of space. The cutter 28 when thus located is protected against injury by the 95 walls of the opening 16 and also by one or more lugs 30 upon the base member 10, if the latter is not thick enough at this point to project beyond the point of the cutter.

100 To open a can the operator first projects the tooth 14 through the head of the can at substantially the center thereof, the parts in their then position being substantially as shown in Figure 2, the numeral 31 designat- 105 ing the can. In accomplishing this preliminary operation, the pressure required to force the tooth 14 through the head of the can may be applied upon the end of the

handle 24. After the tooth 14 has been inserted, the device as a unit is moved upon the tooth 14 as a pivot until the base member 10 is parallel with the head of the can. 5 During the last portion of this movement the tooth 15 is also projected through the head of the can and the lugs 13 rest thereon. When in this position which is shown in Figure 1, the face 18 of the tooth 14 is 10 against the underside of the head of the can, the lugs 13 rest upon the top thereof and the tooth 15 projected therethrough. Thus the can is held against movement relatively to the base member 10 by reason of 15 the teeth 14 and 15. The operator now swings the arm 23 upon its pivot mounting and then about the axis of the post 19 until the cutter is moved to one side of the base member 10. A light pressure is now applied 20 to the handle 24 and the sharpened and pointed end of the cutter 28 is forced through the top of the can.

The operator now grasps the handle portion 11 in one hand and the handle 24 in 25 the other hand and moves the arm 23 about the axis of the post 19. By this movement a circular cut is made through the head of the can, after which the cutter 28 is withdrawn from the end of the can and replaced 30 in the opening 16, the base member 10 moved to the position substantially as shown in Figure 2 and then withdrawn.

The carriage 25 being slidable upon the arm 23, the cutter 28 can be moved toward 35 and away from the axis of the post 19 so as to accommodate cans of various sizes.

For cleansing purposes the carriage 25 carrying with it the cutter 28 may be disassembled by first pulling off the handle 24 40 from the end of the arm 23 and then sliding the carriage off the end of the arm 23. This is a simple operation requiring practically no skill and the carriage may be replaced with equal facility.

45 Within the scope of the appended claims, minor changes and alterations may be made and I would therefore have it understood that I do not limit myself to the exact construction herein shown and described.

50 What I claim as new and desire to secure by Letters Patent, is:

1. A can opener having a member with means connected therewith adjacent to one end for attachment to the head of the can,

a handle at the opposite end and a cutter 55 opening therein, an arm having a universal joint connection with said member, and a cutter movably mounted upon said arm, the said cutter in its inoperative position projecting into the said cutter opening. 60

2. A can opener having a member with parts thereon that project through the can and hold the same against relative movement; a swivel member movably connected therewith; an arm pivotally connected with 65 said swivel member; a carriage slidable upon said arm, portions thereof being upon opposite sides of said arm and lying substantially parallel therewith; and a cutter projecting through said carriage and having 70 an opening therein and through which projects said arm.

3. A can opener having a member with parts thereon that project through the can and hold the same against relative movement; a swivel member movably connected therewith; an arm pivotally connected with 75 said swivel member; a carriage slidable upon said arm, portions thereof being upon opposite sides of said arm and lying substantially parallel therewith; a cutter projecting through said carriage and having an 80 opening therein and through which projects said arm; and spring means for holding said carriage against accidental movement 85 upon said arm.

4. A can opener having a member with parts thereon that project through the can and hold the same against relative movement and having a post thereon; a swivel 90 member pivotally mounted upon said post; an arm pivotally connected with said swivel member, the axis of the pivot mounting of said arm being at substantially a right angle to the axis of said post; a substantially U-shaped carriage slidable upon said arm with its parallel sides substantially parallel with two sides of said arm and having cutter openings therethrough; spring means connected with said carriage having contact 95 with said arm to hold said carriage in its adjusted positions; and a cutter supported in said carriage and through which said arm projects.

In testimony whereof, I have hereunto affixed my signature.

WILLIAM S. PERRY.
